United States Patent Office

Des. 193,161
Patented July 3, 1962

193,161

AIRPLANE

Philip E. Le Veille, Glendale, and Merrill H. Kelly,
Northridge, Calif., assignors to Lockheed Aircraft
Corporation, Burbank, Calif.

Filed Dec. 23, 1960, Ser. No. 63,309

Term of patent 3½ years

(Cl. D71—1)

FIG. 1

FIG. 4

FIG. 2

FIG. 5

FIG. 3

FIGURE 1 is a top perspective view of an airplane embodying our new design;

FIGURE 2 is a top plan view thereof;

FIGURE 3 is a side elevation thereof, the opposite side being substantially the same in appearance as indicated in FIGURES 2 and 4;

FIGURE 4 is a front elevation of the airplane; and

FIGURE 5 is a fragmentary rear elevation thereof.

The dominant features of our design reside in those portions shown in full lines.

We claim:

The ornamental design for an airplane, substantially as shown and described.
